(57) **CLAIM**

We claim the ornamental design for a dampening ring for compressor valve, as shown and described.

DESCRIPTION

FIG. 1 is a perspective view of the dampening ring for compressor valve showing our new design;

FIG. 2 is a top view thereof;

FIG. 3 is a side view thereof;

FIG. 4 is a bottom view thereof; and,

FIG. 5 is an exploded view of the dampening ring for compressor valve in use.

The broken lines shown in the figures are included for the purpose of illustrating environmental structure and form no part of the claimed design.
